The ornamental design for a film case, as shown and described.

DESCRIPTION

FIG. 1 is a top, front and side perspective view of a film case showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof from the left of FIG. 2;

FIG. 7 is a side elevational view thereof from the right of FIG. 2;

FIG. 8 is an exploded perspective view thereof; the contents shown in broken lines for illustrative purposes only and forming no part of the claimed design; and,

FIG. 9 is a cross sectional view taken on line 9—9 of FIG. 4.
